[57] ABSTRACT

A tumbling machine having an endless belt arranged so that the top run of the belt defines with a pair of side walls a V-shaped tumbling chamber in which the mixture of abrasive media and the workpieces are loaded so that at one side of the chamber the workpieces are caused to travel upwardly to a high point, then flow down towards the opposite side of the chamber where they are again conveyed by the belt around the apex of the V.

APPARATUS AND METHOD FOR FINISHING WORKPIECES

This invention relates to an apparatus and method for surface finishing of metal workpieces.

Small workpieces are frequently deburred and/or polished on a production basis in tumbling barrels or vibratory finishing machines. Both of these types of machines have recognized shortcomings with respect to the rate of metal removal and the quality of the finish obtainable on the surface of the workpiece.

The object of the present invention resides in the provision of an apparatus and method for obtaining a high quality finish on workpieces in a minimum amount of time.

More specifically, the invention contemplates the finishing of workpieces by tumbling them with an abrasive or polishing media in a chamber having fixed side walls and a V-shaped bottom wall formed by the top run of an endless belt driven in one direction such that the mass of workpieces and finishing media are caused to travel in said chamber in a manner which promotes a high metal removal rate with a minimum of impingement and a maximum of rubbing or burnishing action.

The machine of the present invention is further characterized by the provision of simple and expedient means for discharging the workpieces and the finishing media from the machine by merely reversing the direction of belt travel and drawing the top run of the belt taut.

Other features and advantages of the present invention will become apparent from the accompanying disclosure and drawings, in which:

FIG. 1 is a side elevational view of a finishing machine according to the present invention.

FIG. 2 is a top view thereof.

FIG. 3 shows the machine as viewed from the discharge end thereof.

FIG. 4 is a fragmentary sectional view of a portion of the machine.

FIG. 5 is a diagrammatic view showing the manner in which the mass of media and workpieces are caused to travel in the machine of the present invention.

FIG. 6 is a fragmentary perspective view within the chamber of the machine showing the endless belt and the mass of finishing media and workpieces.

Referring to FIGS. 1 through 3, the base 10 of the machine comprises a U-shaped stanchion having a pair of laterally spaced upright supports 12 (FIG. 3) on which the spaced apart side walls 14 of the machine housing are mounted. As shown in FIG. 1, each side wall 14 has a downwardly sloping upper edge 16 and two generally converging side edges 18, 20. The machine housing includes a bottom wall 22 extending between the lower portions of side walls 14 and forming a drain trough at the lower end of the machine which slopes downwardly into a sump 24.

Two drive pulleys 26,28 are journaled between side walls 14 at opposite ends of the machine and adjacent the upper edges of the side walls. An endless belt 30 is trained around pulleys 26,28 and around a pair of idler pulleys 32. A belt tightener in the form of pivotally supported arm 34 carrying a roller 36 at its free end is also provided. The belt tightener is adapted to be actuated by a hydraulic cylinder 38 between the two positions shown in FIG. 1.

On the inner surface of one side wall 14 there is fixedly secured a wear plate 42. A second wear plate 44 is mounted on the other side wall 14 for adjustment toward and away from wear plate 42 so that the two wear plates are engaged by the opposite side edges of endless belt 30 and wear plate 44 can be adjusted laterally to compensate for wear in the width dimension of belt 30. A generally V-shaped belt guide 46 which is narrower than belt 30 is secured to the two side walls 14 and extends between the two wear plates 42,44. In FIG. 4 the two legs of the V-shaped belt guide are designated 48, 50 and the rounded apex of the V is designated 52. In FIG. 1 the upper edges of the wear plates 42,44 are designed 51 and in FIG. 4 the opposite side edges of the wear plates are designated 53,55. At the rounded apex 52 the guide plate is provided with a plurality of drain openings 54. It will be observed that leg 48 of guide plate 46 extends along a line generally tangent to pulley 26 and leg 50 extends along a line generally tangent to pulley 28. Leg 48 is more steeply inclined than leg 50. In the embodiment illustrated leg 48 is inclined to the vertical at an angle of about 22° and leg 50 is inclined to the vertical at an angle of about 44°. As will be explained hereinafter, these angles can be varied within a limited range depending upon the speed at which the belt is driven.

Pulleys 26,28 are keyed to shafts each having a sprocket 56 on one end thereof. The output shaft of a speed reducer unit 58 has a pair of sprockets 60 keyed thereto. A pair of chains 62 are trained around both pair of sprockets 60 and 56 so as to rotate the two pulleys 26,28 at the same speed and in the same direction. Belt 30 is driven by the frictional engagement of pulleys 26,28 with the belt. Speed reducer unit 58 is preferably adjustable so as to vary the speed of the belt as desired.

The diagrammatic showing in FIG. 5 illustrates the configuration of the top run 30a of belt 30 and the bottom run 30b of the belt while the machine is in operation. The locations of drive pulleys 26,28 and idler pulleys 32 are determined in relation to the length of belt 30 and the size of the load which the machine is designed to handle such that the upper run 30a of the belt assumes a configuration which generally parallels the shape of guide plate 46 and such that the upper run of the belt will be spaced slightly from guide plate 46 as indicated by the clearance space 64 in FIG. 4. Thus, with the machine operating in the manner illustrated in FIG. 5 the upwardly travelling portion of the top run 30a of the belt is inclined to the vertical at an angle of about 22° and the downwardly travelling portion of the top run 30a of the belt is inclined to the vertical at an angle of about 44°. It will be appreciated however that FIG. 5 actually illustrates the dynamic, not the static, condition of the belt. Furthermore, it will be appreciated that the function of guide plate 46 is merely to prevent the top run 30a of the belt from swaying. Under ideal operating conditions guide plate 46 will be spaced throughout its extent from the underside of the top run 30a of the belt.

In FIG. 6 the workpieces being processed are illustrated as dished-shaped discs 66 and the polishing media or chips are in the form of cones 68 molded from a mixture of a binder, such as a synthetic resin or a ceramic, and abrasive. The use of such preformed synthetic chips, as distinguished from natural stone

chips, is very desirable because natural stone chips tend to splinter whereas the synthetic chips merely wear down in size and are therefore not apt to become wedged between the edges of belt 30 and wear plates 42,44. For some types of finishing operations (polishing, for example, where chips are slippery) it is desirable to have angled cleats 70 on the belt to assist in elevating the mass by means of the upwardly travelling portion of the top run of the belt.

Nozzle 72 is illustrated in FIG. 1 and is located above and slightly inwardly of the upper end of the portion of the belt run travelling upwardly. The nozzle is utilized for directing a spray of water or water containing a nonabrasive detergent over the mass of workpieces and abrasive media as it reaches the upper end of the upward travel. As indicated in FIG. 5 nozzle 72 is connected by a conduit 74 with the outlet of a pump 76 having its inlet connected to sump 24 above the bottom thereof. Thus, with this arrangement the water spray issuing from nozzle 72 cleans the parts and media and then drains into the sump through the drain holes 54 at the lower end of belt guide 50. The fine grindings off of the metal workpieces and the media preforms settles in sump 24 and the substantially uncontaminated water is recirculated back to nozzle 72. Flushing of the workpieces and media is important in order to maintain a clean mass within the chamber of the machine. It serves to accelerate the cutting action of the abrasive media on the workpieces.

The spray nozzle 72 also clears the belt of abrasive chips and workpieces that might otherwise adhere to the belt and become discharged over pulley 26.

In operation the machine is charged with a load of workpieces to be finished and an abrasive media, such as the preformed chips 68. When pulleys 26,28 are driven in a counterclockwise direction as viewed in FIG. 5 the mass assumes the configuration shown in FIG. 5. Generally speaking, the moving mass can be considered as divided into several areas or zones. The most active zone, designated A, may be referred to as the slide zone wherein the parts and media gravitate from the vicinity of high point 78 to the vicinity of low point 80 adjacent the downwardly travelling portion of the belt. The downward slope of the slide area 80 depends upon the shape and surface characteristics of the media and parts. Generally speaking, the slide area inclines downwardly at a fixed angle of between 25° to 35°. The second most active zone in the mass is designated B in FIG. 5 and comprises a layer of the mass adjacent the upper run of the belt. This portion of the mass is active not only because it is being positively driven by the belt, but also because the side walls of the chamber in which the mass is located, namely, wear plates 42,44, remain stationary while the belt is carrying the mass, thus causing additional friction between the layer of the material at each of the sides of the chamber and the material in the center of the mass. The next most active zone is designated C in FIG. 5 and comprises the annular teardrop shape portion surrounding zones A and B. This activity, that is, the relative movement between the parts and the media, in this area is less than in areas A and B. The center area D may be referred to as the dead zone since there is considerably less activity in this zone than in the other zones. However, the parts do not remain stagnant in

area D. Workpieces and media continually work into and out of this area from and into the other areas represented in FIG. 5.

One of the features of the present invention resides in the fact that area D is relatively small in comparison to the size of the mass. This may be explained by the fact that substantial activity occurs in areas B and C as a result of the drag effect on the parts and media by the stationary wear plates while the mass is being positively driven by the belt.

The slope of the upwardly travelling portion of the belt and the speed of the belt are controlled so that as the parts approach the high end of the slide zone A they gently flow around the high point A and gravitate smoothly down toward the low point 80. If the slope of the upwardly travelling portion of the belt is too steep the workpieces roll out of the mass media too freely in the vicinity of high point 78 and simply roll down the slide area A over the mass of abrasive media. This produces relatively little work on the workpieces and prolongs the duration of the finishing cycle. On the other hand, if the slope of the upward travelling portion of the belt is not great enough, the parts tend to churn and remain too long in the high point area 78 where the work being performed on the parts is substantially less than in the slide area A. An inclination of about 22° for this portion of the belt is preferred but inclinations between 17° to 27° are possible.

The slope of the downwardly travelling portion of the top run of the belt is determined such that the slope of the slide zone intersects the plane of the belt at an included angle of less than 90°. This has been found to be desirable to avoid impingement and build-up of the parts and media around the low point 80 of the slide zone A. Impingement should be avoided as much as possible in order to obtain the best quality finish. In the machine of this invention impingement is also avoided by reason of the fact that the downwardly travelling portion of the belt is at a fixed angle (as distinguished from a changing angle as in the case of a straight sided tumbling barrel) and the belt speed can be controlled so that the workpieces flow or fold smoothly into the portion of the mass being driven downwardly by the belt. While an inclination of about 44° to the vertical is preferred, inclinations of between about 40° to 50° are possible.

An extremely important feature of the present invention has to do with the length of a slide zone A in relation to the size of the mass and the size of the least active area D. Slide zone A in a machine of the present invention is substantially greater than the slide area of a tumbling barrel designed to accommodate the same size load and at the same time the size of the inactive area D in the machine of the present invention is substantially smaller than the size of the tumbling barrel designed to accommodate the same load. It follows, of course, that the slide area of a given tumbling barrel can be increased by increasing the diameter of the barrel but it must be remembered that as the diameter of the barrel increases the size of the inactive area in the barrel also increases.

In order to obtain values showing the relative rates of cut and the quality of finish obtainable with a machine of the present invention as compared with a vibratory finishing machine and a tumbling barrel, three identical

loads of small door handles and preformed abrasive chips were run for a period of 4 hours in each of the three machines. The load consisted of 170 lbs. of 9/16 inch $\times$ 9/16 inch cone-shaped chips made of polyesther resin and silica abrasive along with 45 lbs. of zinc handles. A nonabrasive detergent compound was used at the rate of 1 ounce per gallon of water.

The tumbling machine had an octagon shaped cylinder 16 inches long and 30 inches across the flats, and, thus, had an optimum capacity of about 3.1 cubic feet. The vibratory finishing machine also had a 3.1 cubic foot capacity. The tumbling barrel was rotated at 20 r.p.m. and the frequency of the vibratory finishing machine was 2,100 r.p.m. with an amplitude of one-eighth inch. The machine according to the present invention had a width of 8 inches and a radius of 15 inches at the lower rounded end of the V-shaped belt. The two drive pulleys 26,28 had a diameter of 10 inches and were driven at 58 r.p.m. producing a lineal speed of the belt of about 1,800 feet per minute. When the machine was operated with a load of 3.1 cubic feet of chips and handles, the mass assumed the configuration and relative proportions shown in FIG. 5. The results of these tests are shown in Table I.

TABLE I

	Media loss	Part loss	Media loss per oz. of metal loss
Tumbling Barrel	2 lbs.	1 $\frac{1}{2}$ oz.	21.3 oz.
Vibratory Machine	6 lbs.		
Endless Belt Machine	10 oz.	4 oz.	26.5 oz.
	6 lbs.		
	9 oz.	6 $\frac{1}{2}$ oz.	16.1 oz.

Table I clearly shows that the rate of metal removal in the endless belt machine of this invention is substantially higher than in a tumbling barrel or a vibratory finishing machine.

The finish obtained on the handles with the endless belt machine was superior to the finish obtained in the tumbling barrel and in the vibratory finishing machine.

With the machine of the present invention deburring and a smooth matte finish can be obtained by simply operating the machine with a mixture of workpieces and abrasive media. After the desired initial finish is obtained, a polishing compound can be added to the mass in order to obtain a smooth, high luster finish on the workpieces. The successive operations can be performed without removing the mass from the machine or without even stopping the operation of the machine. This feature of the present invention substantially reduces labor costs in comparison with the time and work required for obtaining a high luster, smooth finish on workpieces in a tumbling barrel.

Referring to FIG. 1, it will be noted that when cylinder 38 is actuated, arm 34 is pivoted from its raised to the lowered position. Since roller 36 engages the inside face of the lower run of belt 30, the top run 30a of the belt is caused to gradually shorten in length to a finally taut condition shown at 82 in FIG. 1. Thus, if the direction of rotation of the belt is reversed, that is, pulleys 26,28 rotated clockwise instead of counter-clockwise, as the top run of the belt approaches its taut position the mass of workpieces and media is automatically discharged downwardly over pulley 28 onto a

receiving conveyor or other collector and separating device 84. For this reason it is desirable that speed reducer 58 be not only variable in speed but also in direction of rotation. This facilitates considerably the task of unloading the machine.

I claim:

1. In a machine for finishing workpieces the combination comprising, a pair of rollers spaced apart on parallel axes, one of said rollers being located in a plane above the other roller, an endless belt trained around said rollers, said belt having a length substantially greater than twice the distance between the roller axes, means guiding the belt around said rollers such that the top run of the belt is slack and assumes a generally V-shaped configuration between the rollers which is nonsymmetrical about a vertical axis through the apex of the V, the side of the V adjacent the higher roller being more steeply inclined than the other side of the V, a pair of fixed side plates disposed one adjacent each edge of the belt and cooperating with the top run of the belt to define a generally V-shaped chamber for containing a mass of workpieces and finishing media and means for driving the belt in one direction such that the mass of media and workpieces is caused to flow in said chamber in a path upwardly along said more steeply inclined side of the V-shaped chamber in the direction of the upwardly travelling portion of the top run of the belt, then downwardly across the chamber in the direction toward the downwardly travelling portion of the upper run of the belt at the less steeply inclined side of the V and then downwardly along said last-mentioned side of the V and around the apex of the V to the upwardly travelling portion of the belt, the apex of said V being curved in an upwardly concave direction and the sides of said V being generally flat, the linear extent of said curved apex being small relative to the linear extent of the sides of said V.
2. A machine as called for in claim 1 wherein said belt driving means comprises both of said rollers.
3. A machine as called for in claim 1 wherein said belt driving means have a driving connection with said belt adjacent each of said rollers.
4. A machine as called for in claim 1 wherein said guide means includes means on the underside of the top run of the belt for maintaining the apex of the V-shaped top run of the belt in a generally fixed position between said rollers.
5. A machine as called for in claim 1 wherein said guide means are disposed on the underside of the top run of the belt and are arranged in generally V-shaped fashion with one of the legs of the V adjacent the upwardly travelling portion of the top run of the belt and other adjacent the downwardly travelling portion of the top run of the belt.
6. A machine as called for in claim 1 wherein the upwardly travelling portion of the top run of the belt is inclined to the vertical at an angle of between about 17° and 27°.
7. A machine as called for in claim 6 wherein the downwardly travelling portion of the top run of the belt is inclined to the vertical at an angle of between about 40° to 50°.
8. A machine as called for in claim 1 including belt tightening means for optionally removing said slack from the top run of the belt to cause said top run of the

belt to extent substantially straight in a downwardly inclined angle between said upper and lower rollers.

9. A machine as called for in claim 8 including means for driving the belt such that said straight top run is travelling downwardly in the direction from said upper to said lower roller to discharge the contents of said chamber.

10. A method of finishing workpieces which comprises, charging a mixture of abrasive media and workpieces into a chamber having fixed side walls and a generally V-shaped bottom wall defined by the upper run of an endless belt causing the major portion of said upper run of the belt to assume an angle substantially more steeply inclined to the vertical at one side of the V than at the other side of the V and driving said belt in a direction such that the upper run thereof is travelling upwardly at the more steeply inclined side thereof and downwardly at the less steeply inclined side thereof thereby causing said mass to flow in said chamber in a path extending upwardly in a direction generally parallel to the more steeply inclined, upwardly travelling portion of said bottom wall, then downwardly across said chamber toward the less steeply inclined, downwardly travelling portion of the bottom wall, then downwardly in the direction of travel of the less steeply inclined, downwardly moving portion of the bottom wall and around the apex of the V to the upwardly travelling portion of the bottom wall.

11. The method called for in claim 10 wherein said mass is caused to travel in said upward and downward directions at generally fixed angles inclined relative to the vertical.

12. The method called for in claim 10 wherein at

least the major portion of said mass is caused to travel in said upward direction at a generally fixed angle of between 17° and 27° to the vertical.

13. The method called for in claim 12 wherein at least the major portion of said mass is caused to travel in said downward direction toward the downwardly travelling portion of the bottom wall at a generally fixed angle to the horizontal of about 25° to 35°.

14. The method called for in claim 13 wherein at least the major portion of said mass is caused to travel in said direction of said downwardly moving portion of the bottom wall at a generally fixed angle of about 40° to 50° to the vertical.

15. The method called for in claim 12 wherein the direction of travel of the mass in said downwardly direction toward the downwardly moving portion of the bottom wall and the direction of travel of the mass in the direction of the downwardly moving portion of the bottom wall intersect with an included angle of less than 90°.

16. A machine as called for in claim 1 including means disposed adjacent the upper roller and the upper run of the belt an operable to prevent the workpieces and media in the chamber from being carried upwardly over the top roller as the belt travels thereover and for assisting the workpieces and media to flow in said path downwardly across said chamber.

17. A machine as called for in claim 16 wherein said last-mentioned means comprises nozzle means for directing pressurized liquid streams against the top run of the belt in said chamber and adjacent the upper roller.
